SWITCH PLATE

Gerard J. Feuerbacher, Scarsdale, N. Y., assignor to
Trine Manufacturing Corporation, New York, N. Y., a
corporation of New York

Application November 4, 1955, Serial No. 38,728

Term of patent 14 years

(Cl. D26—13)

Fig. 2.

Fig. 1.

Fig. 3.

Fig. 4.

Fig. 1 is a front elevational view of a switch plate, showing my new design;

Fig. 2 is a left side elevational view;

Fig. 3 is a right side elevational view; and

Fig. 4 is an end elevational view thereof, the opposite end having substantially the same appearance.

I claim:

The ornamental design for a switch plate, as shown and described.
